ATTORNEY

UNITED STATES PATENT OFFICE.

JOSEPH JOHN STOETZEL, OF QUEENS VILLAGE, NEW YORK, ASSIGNOR TO G. & G. ATLAS SYSTEMS, INC., OF NEW YORK, N. Y., A CORPORATION OF NEW YORK.

PNEUMATIC-TUBE APPARATUS.

Application filed April 17, 1926. Serial No. 102,675.

This invention relates to improvements in pneumatic tube apparatus, and particularly to the controlling devices for controlling the flow of air through the system.

5 The object of my invention is to provide such a controlling device which is sensitive to the pressure conditions within the system and which, as a result, will automatically regulate the amount of air flow in accordance with the load imposed upon the system at all times.

In my copending application, Serial No. 62,965, filed Oct. 17, 1925, I have disclosed a controlling device which in many ways resembles the controlling device of my present invention. The valve of said copending application is, however, so constructed that it is always in one of two positions. That is, it is either in its closed position or 20 in its fully open position. According to my present invention the valve is closed when no carrier is being transmitted, and when one or more carriers are being transmitted it is open—not fully open always—but at all times open just enough to establish the amount of air flow that the load requires.

The principal structural difference between these two devices is that in the device 30 of my copending application the valve opens in a direction against the current of air flow, whereas in the device of my present application the valve opens in the direction of the air current. As a result of this arrangement my improved device operates not only to govern the amount of flow while carriers are being transmitted, but serves also as a relief valve for cooperation with a constant speed suction producing device to 35 relieve excessive loads thereon when no carrier is in transit.

In the accompanying drawing, Fig. 1 illustrates a conventional pneumatic tube system to which my present invention is applicable; Fig. 2 is a longitudinal sectional view of the controlling device of my invention; and Fig. 3 is a detail view taken on the sectional line 3—3 of Fig. 2.

The pneumatic tube system shown in Fig. 50 1 embodies the vacuum drum 10, the suction tube 11 and the transmitting tubes 12, 13 which are connected by the intermediate terminal 14 in the manner well understood in the art. At the intermediate terminal 55 there is the carrier exit 15 controlled by the

hinged door and the similarly controlled carrier entrance 16. At the extreme end of the tube 13 is the open bell-mouth 17.

The controlling device 18 of my invention is interposed in the suction tube 11. This 60 controlling device includes an orifice 19 through which air is adapted to flow and which is controlled by the valve 20. This valve is mounted upon the valve rod 21, to the other end of which valve rod is connected the flexible diaphragm or other pneumatic device 22 for opening the valve, as will be described later. This diaphragm 22 divides the casing 23 into two chambers, namely, the chamber 24 to the left of the 65 diaphragm, which is open to the atmosphere through the orifice 25, and the chamber 26 at the right of the diaphragm, which is in communication with the transit tube 11 through the passage 27. By reason of this 70 communication the chamber 26 is normally maintained at the pressure existing within the transit tube 11 above the controlling device.

The valve 20 is normally held in the 80 "closed" position shown in Fig. 2 by the relatively strong spring 29 which surrounds the right hand end of the valve stem 21 and the tension of which may be adjusted by means of the adjusting sleeve 30 which may be held in adjusted position by the lock nut 31. In referring to the "closed" position of the valve 20 I mean the position such as shown in Fig. 2, in which the valve is held slightly off its seat to permit of a slight 90 flow of air through the orifice 19. The amount of this opening, and therefore the amount of "minimum flow", is determined by the position of the adjusting screw 32 which contacts with the left hand end of the 95 valve stem 21.

The passage 27 between the diaphragm chamber 26 and the transit tube 11 is preferably provided with an opening 33 to the atmosphere, which is controlled by the 100 poppet valve 34 normally held closed by gravity. This poppet valve is mounted on one end of a pivoted lever 35, the other end of which extends within the transit tube and is provided with a vane 36.

The particular point of interest in the controlling device I have just described is the fact that the valve 20 opens with the current of air flow instead of against it, as in the case of my copending application.

By so arranging the valve it is converted into a relief valve which not only accommodates itself to the load in the line while carriers are being transmitted, but also prevents the building up of an excessive vacuum in the suction drum when no carriers are being transmitted. I shall now describe the manner in which these functions are performed by the valve.

- 5 10 When no carrier is being transmitted in the tube the minimum flow is maintained as above described. If, however, the minimum flow provided by the adjustment of the screw 32 should prove insufficient to prevent 15 the suction producing device from building up an excessive vacuum in the suction drum, then that vacuum will operate upon the valve 20 and open it slightly so as to permit a larger minimum flow and thus reduce the 20 vacuum in the suction drum to the desired amount. Of course, if there are a number of lines connected to a single suction drum, as is usually the case, the operation of a single one of the controlling devices as a 25 relief valve would usually take care of any excess of vacuum formed in the drum.

Turning now to the operation of the valve upon the insertion of a carrier and during its transmission, when the carrier is inserted 30 in the bell-mouth 17 or the intermediate entrance 16, it acts as a plug, stopping the communication between the controlling devices and the atmosphere through the bell-mouth. As a result, the minimum flow 35 through the orifice 19 rarefies the air in the diaphragm chamber 26 so that the atmospheric pressure within the diaphragm chamber 24 exerts a pressure on the diaphragm tending to push it toward the right to open 40 the valve. This unbalanced pressure and tendency to open the valve is augmented by the unbalanced pressure on the valve 20 and the kinetic energy of the flow of air through the orifice 19. These combined factors 45 result in opening the valve against the pressure of the spring 29. This spring, however, as above described, is relatively strong compared, for example, to the corresponding spring in my copending application, and as 50 the result, if the load in the line is reduced, as for example by the carrier passing through a vertical drop in the line, the decrease in the vacuum within the diaphragm chamber 26 permits this spring to partially 55 or wholly close the valve 20. When the carrier again imposes a greater load upon the line the valve will be again opened as above described.

When the carrier leaves the line there is an immediate rush of air through the line, and this rush of air may be utilized through the vane 36 to open the poppet valve 34 and thus admit atmospheric pressure to the diaphragm chamber 26 to assist in closing the valve 20. Because of the strong spring 29,

which my present arrangement makes possible, I find it unnecessary to employ any vane 36 and its cooperating parts for closing the valve 20 except in excessively long lines, and even in such lines I find it can be dispensed with without serious inconvenience or loss of efficiency.

I have referred above to the fact that my present structure permits me to use a relatively strong spring 29. The reason this 75 is permitted is because the valve 20 opens as a relief valve in the direction of flow of the air current and therefore, as above indicated, the unbalanced pressure on the diaphragm 80 22 is augmented by the action of the unbalanced pressure on the valve itself as well as the kinetic energy on the valve produced by the flow of air in the direction of its opening.

So far as I am aware, it has never before 85 been proposed to provide a valve of this kind which opens as a relief valve in the direction of the line of flow. In the device of my copending application, and in other devices of similar construction, the valve opens in the direction against the air current. As the result, the spring which normally tends to hold the valve closed has to be relatively light or otherwise the unbalanced pressure on the diaphragm resulting from the insertion of a carrier would be insufficient to open the valve against the direction of current flow. Accordingly, the valve of my copending application operates as a snap valve, snapping open upon the insertion of a carrier and then snapping closed again upon the exit of the carrier. It has no intermediate position. The distinction between such operation and the operation of the device described herein is believed obvious.

I may apply my present invention to controlling devices of various forms, the particular form shown in the drawing being merely one illustration of the application of 110 this invention.

The terms and expressions which I have employed are used as terms of description and not of limitation, and I have no intention, in the use of such terms and expressions, of excluding any equivalent of features shown and described, or portions thereof, but recognize that various modifications are possible within the scope of the invention claimed.

I claim:

1. In a pneumatic tube system, a transmitting tube, a casing communicating with said transmitting tube and provided with an orifice, means for producing a flow of air through said orifice, a valve for said orifice adapted to control the flow of air therethrough, said valve being adapted to open in the direction of said flow, spring means tending to close said valve, and means re-

sponsive to the pressure conditions in the transit tube for opening said valve.

2. In a pneumatic tube system, a transmitting tube, a casing communicating with said transmitting tube and provided with an orifice, vacuum producing means beyond said casing adapted to produce a flow of air through said orifice, a valve for said orifice adapted to control the flow of air there-through, said valve being adapted to open in the direction of said flow, spring means tending to close said valve, and means responsive to the pressure conditions in the transit tube for opening said valve.
3. In a pneumatic tube system, a transmitting tube, a casing communicating with said transmitting tube and provided with an orifice, means for producing a flow of air through said orifice, a valve for said orifice adapted to control the flow of air there-through, spring means tending to close said valve, means normally holding said valve slightly open to permit a slight flow through
4. In a pneumatic tube system, a transmitting tube, a casing communicating with said transmitting tube and provided with an orifice, vacuum producing means beyond said casing adapted to produce a flow of air through said orifice, a valve for said orifice adapted to control the flow of air there-through, spring means tending to close said valve, means normally holding said valve slightly open to permit a slight flow through

said orifice, the means for producing the flow of air through said orifice being adapted to exert pneumatic force on said valve in the direction of its opening, whereby said valve responds to an excess of such force by opening and thus relieves such excess.

- 25
  - 30
  - 35
  - 40
4. In a pneumatic tube system, a transmitting tube, a casing communicating with said transmitting tube and provided with an orifice, vacuum producing means beyond said casing adapted to produce a flow of air through said orifice, a valve for said orifice adapted to control the flow of air there-through, spring means tending to close said valve, means normally holding said valve slightly open to permit a slight flow through said orifice, said vacuum producing means being adapted to exert pneumatic force on said valve in the direction of its opening, whereby said valve automatically opens to relieve any excess of vacuum which may be produced by said vacuum producing means.

JOSEPH JOHN STOETZEL.
